OPHTHALMIC MOUNTING

Carl E. H. Colliander, Providence, R. I., assignor
to Lorgnettes, Inc., Providence, R. I., a corpora-
tion of Rhode Island

Application July 15, 1935, Serial No. 31,333

9 Claims. (Cl. 88—42)

The present invention relates to ophthalmic mountings, more particularly mountings comprising a raised bridge, and its chief object is to provide a new and improved detachable connection between the bridge and the lens-holding members of mountings of this character, in order that the stock required to be kept on hand by the ordinary optician may be reduced to the minimum, and in order that any broken or un-
stylish part, whether lens rim or bridge, may readily be replaced by another.

The invention will be explained in connection with the accompanying drawing, in which Fig. 1 is a front elevation of an ophthalmic mounting constructed according to a preferred embodiment of the present invention; Fig. 2 is a corresponding fragmentary, rear elevation of the same; Fig. 3 is a fragmentary perspective of a portion of the lens rim shown in Fig. 2, upon a larger scale, the guard being removed for clearness; Fig. 4 is a similar perspective of the corresponding end of the bridge; Fig. 5 is a horizontal section, upon the same larger scale, the section being taken upon the line 5—5 of Fig. 2, looking downward in the direction of the arrows; and Fig. 6 is a rear elevation of the end of the bridge shown in Fig. 4, separated from the corresponding rim, which is shown in longitudinal, vertical section.

The ophthalmic mounting of the present invention comprises, in its preferred embodiment, two substantially circular, metal, lens-holding rims 2 and 4, connected together by a metal bridge, and having guards 38. The rims 2 and 4 are respectively provided with pockets 8 and 10, open at the top 12 and also at the bottom 14, but closed at the lower portions of the front 29, the back 31 and the sides 25 that are disposed opposite to the inner walls 5 and 9 of the pockets 8 and 10. It is preferred to have the bottoms 14 open to prevent the accumulation of dust and the like. Furthermore, a better support is obtained by having the depending portions 18 and 20 of the bridge extend through the bottoms 14 of the pockets. The pockets 8 and 10 taper downward from the top 12 toward the bottom 14. The inner wall 5 of the pocket 8 is a continuation of the outer wall 7 of the rim 4, and the inner wall 9 of the pocket 10 is similarly a continuation of the outer wall 11 of the rim 2.

The ophthalmic mounting of the present invention is of the type that is supported upon the face by the guards 38, that rest upon the sides of the nose, in cooperation with temples

6. The bridge is, therefore, provided with an intermediate, raised portion 16, and the said two terminal or end portions 18 and 20 depending from the raised portion 16. The lower extremities of the end portions 18 and 20 taper downward, as illustrated at 22, to correspond to the downward taper of the pockets 8 and 10. These lower extremities 22 are thus adapted to be slid into their corresponding pockets 8 and 10, through the open tops and bottoms 12 and 14, and will then fit tightly therein, with the end portions 18 and 20, and particularly their lower parts or extremities 22, conforming substantially to the shapes of the respective rims 2 and 4. A considerable part of the portions 18 and 20 contact with the respective outer surfaces 7 and 11 of the rims 2 and 4.

Each bridge end portion 18 and 20 is detachably held in place in its corresponding pockets 8 and 10 by a transversely movable clamp at 20 the upper end of each pocket. To this end, the upper portion of the rear side wall of each pocket is split or divided at 13 so as to provide two walls 15 and 17 on opposite sides of the split. The wall 15 is provided with an interiorly 25 threaded, hollow element 19, and the wall 17 with a smooth-bored, hollow element 21. A screw 26 may be loosely mounted in the element 21 and threaded in the element 19. The wall 17 merges in a wall 23 at right angles thereto, 30 which is substantially a continuation of the wall 25 of the pocket, except that it is separated therefrom by a slot 27. The wall 17 is similarly separated from the wall 31 by a slot 33. By tightening the screw 26, therefore, it is possible 35 to actuate the clamp walls 17 transversely toward the clamp walls 15, into engagement with the respective end portions 18 and 20 of the bridge. A very effective bridge-holding pocket 40 is thus provided, having a wall the upper portion of which is slit longitudinally at 13 in the side 31 and transversely at 27 and 33 to form the transversely movable clamp wall 17. To detach the bridge, all that is necessary is to unscrew the screw 26. The extremities 22 and 24 of the bridge may then be freely moved upward, through the open tops 12 of the pockets 8 and 10, and the bridge replaced by another bridge of different shape, size, or style.

The lower portions of the bridge thus conform in all respects to, and fit snugly against, the outer surfaces 7 and 11 of the rims, the end portions 18 and 20 of the bridge are detachable from the rims 2 and 4, and yet the parts are 55

nevertheless securely held together in assembled relation.

Each depending portion 18 and 20 of the bridge has a tapering, clamping face 35, formed by cutting diagonally into the bridge at 37 and 39, so as exactly to receive the wall 23 between the cuts 37 and 39. When the screw 26 is tightened, therefore, the wall 23 will clamp against the tapering clamping face 35. The cuts 37 and 10 39 constitute shoulders at the ends of the clamping face 35, between which shoulders the clamp wall 23 is received.

Adjustments for pupillary distance may be effected in the portion 16 of the bridge, but if 15 too drastic an adjustment is required, all that is necessary is to replace the bridge by another. The optician is not, therefore, required to keep on hand more than a minimum number of bridges and rims, of different sizes, shapes and 20 styles, as he is now enabled to assemble any style or size of bridge, with any style or size of rim to produce a mounting suitable to the requirements of any patient. Similarly, if any part, whether lens rim or bridge, becomes broken 25 or unstylish, it may readily be replaced by another.

It will be understood that the invention may be further modified by persons skilled in the art, and such modifications are considered to be within the spirit and scope of the invention 30 as defined in the appended claims.

What is claimed is:

1. An ophthalmic mounting having, in combination, a bridge member having an intermediate raised portion and two end portions depending from the raised portion, two lens-holding members each having a pocket open at the top and the bottom, the inner wall of each pocket being a continuation of the outer wall 40 of the corresponding lens-holding member, the end portions being shaped to conform to the shape of the lens-holding members throughout considerable portions of their lengths and the lower extremities of the respective end portions 45 being shaped to correspond to the shape of the pockets, whereby the said lower extremities may be slid into the pockets through the open tops and bottoms so as to be caused to fit tightly in their corresponding pockets and so that the end 50 portions will be caused to contact with the lens-holding members throughout the said considerable portions of their lengths, and means detachably engaging the said lower extremities for detachably securing the said lower extremities 55 in their respective pockets, the said lower extremities being freely movable into and out of their respective pockets through the open tops of the pockets when the detachable securing means are ineffective.

60 2. An ophthalmic mounting having, in combination, a bridge member having an intermediate raised portion and two end portions depending from the raised portion, two lens-holding members each having a pocket open at the top and a transversely movable clamp, the inner 65 wall of each pocket being a continuation of the outer wall of the corresponding lens-holding member, the end portions being shaped to conform to the shape of the lens-holding members throughout considerable portions of their lengths and the lower extremities of the respective end portions being shaped to correspond to the shape of the pockets, whereby the said lower extremities fit tightly in their corresponding 70 pockets and the end portions contact with

the lens-holding members throughout the said considerable portions of their lengths, and means for actuating the clamps transversely into engagement with the respective end portions for detachably securing the said lower extremities in their respective pockets, the said lower extremities being freely movable into and out of their respective pockets through the open tops of the pockets when the clamps are ineffective. 10

3. An ophthalmic mounting having, in combination, a bridge member having an intermediate raised portion and two end portions depending from the raised portion, two lens-holding members each having a pocket the upper 15 portion of the wall of which is slit longitudinally and transversely to form a transversely movable clamp, the inner wall of each pocket being a continuation of the outer wall of the corresponding lens-holding member, the pockets 20 being open at the top and bottom and being shaped to conform to the lower extremities of the respective end portions, whereby the said lower extremities may be slid into the pockets through the open tops and bottoms so as to be caused to fit tightly in their corresponding pockets, the lower parts of the end portions conforming substantially to the shapes of the lens-holding members when the said lower extremities are thus caused to fit tightly in the pockets, 30 and screw means for actuating the clamps transversely into engagement with the respective end portions for detachably securing the said lower extremities in their respective pockets, the said lower extremities being freely 35 movable into and out of their respective pockets through the open tops of the pockets when the screw means are ineffective.

4. An ophthalmic mounting having, in combination, a bridge member having an intermediate 40 raised portion and two end portions depending from the raised portion, each end portion having a tapering clamping face, two lens-holding members each having a pocket open at the top, the inner wall of each pocket being a 45 continuation of the outer wall of the corresponding lens-holding member, the end portions being shaped to conform to the shape of the lens-holding members throughout considerable portions of their lengths and the lower 50 extremities of the respective end portions being shaped to correspond to the shape of the pockets, whereby the said lower extremities fit tightly in their corresponding pockets and the end portions contact with the lens-holding members throughout the said considerable portions of their lengths, and means for clamping against the tapering clamping face for detachably securing the said lower extremities in their respective pockets, the said lower extremities being 60 freely movable into and out of their respective pockets through the open tops of the pockets when the clamping means are ineffective. 55

5. An ophthalmic mounting having, in combination, a bridge member having an intermediate 65 raised portion and two end portions depending from the raised portion, each end portion having a tapering clamping face with a shoulder at each end thereof, the lower extremities of the end portions being tapering, two lens-holding 70 members each having a correspondingly tapering pocket open at the top and the bottom, whereby the said lower extremities fit tightly in their corresponding pockets, the inner wall of each pocket being a continuation of the outer 75

wall of the corresponding lens-holding member, and the upper portion of the wall of each pocket being slit longitudinally at one side and transversely to form a transversely movable clamp 5 and having a screw at the said side, the lens-holding member having a screw-threaded opening into which the screw is adapted to be threaded to cause the clamp to be actuated transversely into engagement with the tapering clamping 10 face between the shoulders for detachably securing the said lower extremities in their respective pockets, the said lower extremities being freely movable into and out of their respective pockets through the open tops of the pockets 15 when the screws are ineffective.

6. An ophthalmic mounting having, in combination, a metal bridge member having an intermediate raised portion and two end portions depending from the raised portion, each end 20 portion having a tapering clamping face with a shoulder at each end thereof, the lower extremities of the end portions being tapering, two substantially circular metal lens-holding rims each having a correspondingly tapering pocket 25 open at the top and the bottom, whereby the said lower extremities fit tightly in their corresponding pockets, the inner wall of each pocket being a continuation of the outer wall of the corresponding lens-holding rim, the lower parts 30 of the end portions conforming substantially to the shapes of the rims when the said lower extremities fit tightly in the pockets, and the upper portion of the wall of each pocket being slit longitudinally at one side and transversely 35 to form a transversely movable clamp and having a screw at the said side, the lens-holding member having a screw-threaded opening into which the screw is adapted to be threaded to cause the clamp to be actuated transversely into engagement with the 40 corresponding end portion for detachably securing the said lower extremities in their respective pockets, the said lower extremities being freely movable into and out of their respective pockets through the open tops of the pockets 45 when the screws are ineffective.

7. An ophthalmic mounting having, in combination, a bridge member having an intermediate raised portion and two end portions depending from the raised portion, two lens-holding members each having a pocket open at the top and the upper portion of the wall of which is slit longitudinally and transversely to form a transversely movable clamp, the inner wall of 50 each pocket being a continuation of the outer wall of the corresponding lens-holding member, the lower parts of the end portions conforming substantially to the shapes of the lens-holding members when the lower extremities of the end portions are inserted in the pockets, and means for actuating the clamps transversely into engagement 55 with the clamping face between the shoulders for detachably securing the said lower extremities in their respective pockets, the said lower extremities being freely movable into and out of their respective pockets through the open tops of the pockets when the clamps are ineffective.

detachably securing the said lower extremities in their respective pockets, the said lower extremities being freely movable into and out of their respective pockets through the open tops of the pockets when the clamps are ineffective. 5

8. An ophthalmic mounting having, in combination, a bridge member having an intermediate raised portion and two end portions depending from the raised portion, two lens-holding members each having a tapering pocket open 10 at the top and the upper portion of the wall of which is slit longitudinally at one side and transversely to form a transversely movable clamp and having a screw at the said side, the inner wall of each pocket being a continuation 15 of the outer wall of the corresponding lens-holding member, the end portions being shaped to conform to the shape of the lens-holding members throughout considerable portions of their lengths and the lower extremities of the 20 respective end portions being shaped to correspond to the shape of the pockets, whereby the said lower extremities fit tightly in their corresponding pockets and the end portions contact with the lens-holding members throughout 25 the said considerable portions of their lengths, the lens-holding member having a screw-threaded opening into which the screw is adapted to be threaded to cause the clamp to be actuated transversely into engagement with the 30 corresponding end portion for detachably securing the said lower extremities in their respective 35 pockets, the said lower extremities being freely movable into and out of their respective pockets through the open tops of the pockets when the screws are ineffective.

9. An ophthalmic mounting having, in combination, a bridge member having an intermediate raised portion and two end portions depending from the raised portion, each end portion 40 having a clamping face with a shoulder at each end thereof, two lens-holding members each having a pocket open at the top and the upper portion of the wall of which is slit longitudinally and transversely to form a transverse- 45 ly movable clamp, the inner wall of each pocket being a continuation of the outer wall of the corresponding lens-holding member, the lower parts of the end portions conforming substantially to the shapes of the lens-holding members 50 when the lower extremities of the end portions are inserted in the pockets, and means for actuating the clamps transversely into engagement with the clamping face between the shoulders for detachably securing the said lower extremities in their respective pockets, the said lower extremities being freely movable into and out of their respective pockets through the open 55 tops of the pockets when the clamps are ineffective.

CARL E. H. COLLIANDER.
